UNITED STATES PATENT OFFICE.

ALBERT LEE ELIEL, OF LOS ANGELES, CALIFORNIA.

SIGNAL.

1,410,392.

Specification of Letters Patent. Patented Mar. 21, 1922.

Application filed January 15, 1919. Serial No. 271,283.

To all whom it may concern:

Be it known that I, ALBERT LEE ELIEL, a citizen of the United States, residing at Los Angeles, in the county of Los Angeles and State of California, have invented new and useful Improvements in Signals, of which the following is a specification.

This invention relates to signals, generally, and more particularly to vehicle signals, whereby the drivers of automobiles and other vehicles may indicate the direction in which a turning movement of the vehicle is to be executed. Many devices of this character have been previously experimented with, and the invention has for its object to provide a simple, inexpensive, attractive, reliable, conveniently operated, positive and practical device of this character, which may be used in long continued service without failure and which in the respects mentioned will be superior to previous devices attempted to be operated. With the above and other objects in view, the invention consists in the novel and useful formation, provision, combination, association and relative arrangement of parts, members and features, all as hereinafter described, shown in the drawings, and finally pointed out in claims.

In the drawings:

Figure 1 is a fragmentary rear elevation of a portion of the dashboard and of the windshield of a motor vehicle, showing the signal device of the invention installed, in two units, in connection with such dash board;

Figure 2 is an enlarged rear side elevation of one of the signal devices shown in Figure 1, in detached position;

Figure 3 is a diagrammatic view illustrating the source of electrical energy and the electrical path for such energy, all employed in the operation of an audible signal member and a visible signal member used in connection with the signal device of the other features;

Figure 4 is a top plan view of the structure shown in Figure 2, partly broken away for convenience in illustration;

Figure 5 is a detail transverse sectional view taken upon the line x_5-x_5 Fig. 2, and looking in the direction of the appended arrows;

Figure 6 is a detail transverse sectional

view taken upon the line x_6-x_6 , Figure 2, and looking in the direction of the appended arrows;

Figure 7 is a detail transverse sectional view, taken upon the line x_7-x_7 , Figure 2, and looking in the direction of the appended arrows;

Figure 8 is a detail transverse sectional view taken upon the line x_8-x_8 , Figure 2, looking in the direction of the appended arrows;

Figure 9 is a detail transverse sectional view taken upon the line x_9-x_9 , Figure 2, and looking in the direction of the appended arrows;

Figure 10 is a detail transverse sectional view taken upon the line $x_{10}-x_{10}$, Figure 2, and looking in the direction of the appended arrows;

Figure 11 is a detail sectional view of features of the construction shown particularly in Figure 6, the same being fragmentary, and taken upon the line $x_{11}-x_{11}$, Figure 6, and looking in the direction of the appended arrows;

Figure 12 is an end view of the construction shown in Figures 2 and 4, looking in the direction of the large arrow at the right hand end of Figure 4; and,

Figure 13 is an isometric view of an element of the signal device shown in Figures 1, 2 and 4, the same being in detached position.

Corresponding parts in all the figures are designated by the same reference characters.

Referring with particularity to the drawings, the improved signal therein disclosed comprises a casing or housing A, a signal member B normally housed or chambered therein and adapted to be projected therefrom into signalling position, means of illumination C carried by said signal member, and an audible signal means D within said housing or casing. Two of such signals are shown as mounted upon the dash E of a motor vehicle, in Figure 1, one at each side of the dash, so that the signal members B of the same may be respectively projected to left and to right into signalling positions. The casings or housings A are provided with ears 14 for attaching the same to such dash. F designates switch means mounted upon the dash and whereby the signal means C

and the signal means D, or the signal means D alone, may be operated, by electrical energy from a source G, such as a battery, or from the electrical circuit used in operating the motor vehicle. The audible signal D may comprise the usual electro-magnetically operated bell 15, of any standard or preferred form, the same being mounted within the casing A at the end thereof opposite to that from which the signal member B is projected.

The signal member B is preferably composed of a pair of metallic plates 16, which are stamped out of sheet metal plates, and are oppositely bowed in their median portions, as at 16^a, to produce a central chamber 16^b within which may be accommodated the various features of circuit wiring, and the like, hereinafter outlined in detail. At the outer end of this signal member B is provided the lighting signal means C, the same preferably consisting of an ordinary incandescent bulb 17 which is accommodated in an opening 17^a produced through the outer end portions of the plates 16, such incandescent bulb being fitted into the usual socket, accommodated within an enlargement 16^c of the chamber 16^b produced by increasing the lateral bulge of each plate 16. These plates 16 are suitably secured together, as by rivets 18 and the top and bottom edge portions of the joined plates 16 are provided with opposed ears 16^d which jointly provide projections received within ways 19 formed in the top and bottom of the casing or housing A, such ways being preferably merely channels in the metallic formation of such casing. The bulb 17 is held detachably in place by a pair of curved spring fingers 21, each of which is secured to one of the plates 16, as at 20, and embraces the neck of the bulb at one side, acting as a guard and safety means for holding the bulb firmly in position. H designates an operating member 45 for the signal member B, the same consisting of a rod or arm 22 which is secured at one end, as at 23, to the signal member B, the same being curved outwardly and extended parallel with the casing A and terminated at the other end in a finger piece or hand-hold 22^a, and being confined by a keeper 24 which is at the end of an elongated slot or opening 25 produced in the outer side wall of the casing A, and which permits the rod 22 to travel jointly with the projection and retraction of the member B. The rod 22 is secured to the sliding member B as shown in Figures 6 and 11 in detail, being provided with a reduced end portion 22^b which passes through the plates 16 of the member B at the bulging portions 16^a thereof, there being a washer 22^c passed upon such reduced end portion and accommodated within the chamber 16^b. Between washers 60 26 at the extreme end portion of such re-

duced end portion 22^b is secured one end of a contact finger 27, which has a brushing contact with an elongated circuit member 28 held within the casing A and depending from the top thereof. An end nut 29 is applied to a still further reduced and threaded portion 30 at the end of the rod 22, thus holding the contact member 27, the nuts 26, the washer 22^c and the rod 22, all in assemblage in connection with the member B and its plates 16. K designates a door or closure for the outer end of the casing A, the same being a drop door connected with the top wall of the casing by a spring hinge 31 so that it will automatically remain closed when the member B is housed.

In order to energize the lamp 17 and the bell 15, so that the means C and D may be operated in signalling, suitable electrical circuit members are provided. These are part of an electrical path *k*, which extends from the switch F to and through the battery or other electrical energy source G, to and through the electro-magnetic element of the bell signal D, and to and through the incandescent lamp bulb element of the signal means C. This electrical path includes any preferred and suitable conducting members, including insulated wires, and those which supply the lamp 17 extend within the chamber 16^b in the member B. As shown in the diagrammatic representation in Figure 3, the electrical path extends from the battery or source G to the bell 15, and likewise from the battery to the elongated circuit member 28 within the casing A. Between the contact member 27 and the bell 15 on the one hand and the contact member 27 and the lamp 17 on the other hand is provided the double pole two-way switch F which is adapted to close a circuit through the electrical path and energize the bell 15 while de-energizing the light 17 or to close a circuit through the electrical path and energize both the bell 15 and the lamp 17.

In the operation of the device, the switch F is operated to cause the operation of either the bell alone or the lamp and bell together, in accordance with whether the period of use be one of darkness or light. Then, when it is desired to set the signal, the switch having so been operated, the operating member H is grasped at the hand-hold 22^a and the member B is projected into visible position, at one side or the other of the vehicle, the operation of both of the signals being the same but only one being used, and at the proper side, at any one time. When the bell and lamp are jointly operated, the interruptions in the electrical path caused by the intermittent action in the electro-magnetic means operating the bell, will cause pulsations in the light emitted by the lamp 17, and this will produce a lighting effect in the means C which will clearly distinguish

the same from any other lamp or light upon the roadway. This pulsating light effect will, in extended use of the invention, be associated by drivers and pedestrians with 5 the use of a signal of this type, and thus the signal will be far more effective than it would be were the light of the usual non-pulsating or steadily-burning type.

It is manifest that many variations may 10 be made in practicing the invention, in departure from the exact construction shown in the drawings and described in the preceding description. All this variation may 15 take place without departing from the real spirit of the invention.

Having thus disclosed my invention, I claim and desire to secure by Letters Patent:

1. In a signal of the character disclosed, 20 including a housing provided with ears for attachment to an object; a signal member adapted for confinement within or projection from said housing into signaling position; said signal member being composed of 25 plates bowed in their median portions to form a central chamber; said signal member plates being provided at their opposed edges with marginal projections and the said housing being formed with opposed ways receiving 30 said projections to guide said signal member in its movement; said housing being formed with an extended slot; and an arm joined with the signal member and projecting through said slot, whereby the signal 35 member may be moved.

2. In a signal of the character disclosed, 40 including a housing provided with ears for attachment to an object; a signal member adapted for confinement within or projection 45 from said housing into signaling position; said signal member being composed of plates bowed in their median portions to form a central chamber; said signal member plates being provided at their opposed edges 50 with marginal projections and the said housing being formed with opposed ways receiving said projections to guide said signal member in its movement; said housing being formed with an extended slot; and an arm joined with the signal member and projecting through said slot, whereby the signal 55 member may be moved; said signal mem-

ber having its central chamber enlarged at one end and communicating with an opening 55 formed adjacent an end of the signal member; there being an incandescent bulb accommodated in said opening and enlarged end of the central chamber of the signal member; and means for energizing said bulb when the signal member is projected from 60 the housing.

3. In a signal of the character disclosed, 65 including a housing provided with ears for attachment to an object; a signal member adapted for confinement within or projection from said housing into signaling position; said signal member being composed of plates bowed in their median portions to form a central chamber; said signal member plates being provided at their opposed edges 70 with marginal projections and the said housing being formed with opposed ways receiving said projections to guide said signal member in its movement; said housing being formed with an extended slot; and an arm joined with the signal member and projecting through said slot, whereby the signal member may be moved; said signal member having its central chamber enlarged at one 75 end and communicating with an opening 80 formed adjacent an end of the signal member; there being an incandescent bulb accommodated in said opening and enlarged end of the central chamber of the signal member; and means for energizing said bulb when the signal member is projected from 85 the housing; said means including a source of electrical supply and an extended electrical path joined therewith, said electrical path including an elongated circuit member 90 within the housing, a contact finger joined with the signal member for brushing contact with the circuit member, and conducting wires confined within the central chamber having connection with the incandescent 95 bulb, circuit member and contact finger.

In testimony whereof, I have signed my name to this specification in the presence of two subscribing witnesses.

ALBERT LEE ELIEL.
